UNITED STATES PATENT OFFICE.

STEPHEN G. BALDWIN, OF MARION, INDIANA.

INK-WELL.

SPECIFICATION forming part of Letters Patent No. 781,868, dated February 7, 1905.

Application filed May 26, 1904. Serial No. 209,699.

To all whom it may concern:

Be it known that I, STEPHEN G. BALDWIN, a citizen of the United States, residing at Marion, in the county of Grant and State of Indiana, have invented certain new and useful Improvements in Ink-Well; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to ink-wells, and has for its object to provide a device of this class which is simple in its construction, easy and cheap to manufacture, and composed of a minimum number of parts.

A further object of my invention is to provide an ink-well which effectually seals the ink against atmospheric action.

A further object of my invention is to provide a combined ink-well and pen holder and wiper.

With all these objects in view my invention consists in the novel construction of the several parts of the ink-well.

My invention also consists in the particular arrangement of the parts and in the location of the shot, the purposes of which will be first described and afterward specifically pointed out in the appended claims.

Referring to the accompanying drawings, Figure 1 is a perspective view of the ink-well. Fig. 2 is a vertical section through the same, and Fig. 3 is a like view showing a slight modification.

Like numerals of reference indicate the same parts throughout the several figures, in which—

1 indicates the ink-well, which is composed of an outer receptacle 2, which may be of any convenient shape or of the shape shown in Fig. 1. Referring to Fig. 2, it will be seen that the outer receptacle 2 is integral with the inner receptacle 3, which inner receptacle carries the ink. In this construction it is of course necessary to form the ink-well of glass or a like material which can be molded or blown. In Fig. 3, however, the inner recep-

tacle 3 is not a part of or secured to the outer receptacle 2, and when following this construction the outer receptacle may be made of wood or any suitable material, while the inner ink-receptacle 3 may be made of glass, hard rubber, or any material suitable for holding ink.

4 indicates a cover having a cone-shaped portion 5 in the center thereof and extending down in the ink-receptacle 3, the extreme end 6c of said cone-shaped portion entering the ink in the said receptacle, as shown in Figs. 2 and 3, the size of the opening sufficient to freely admit of a pen being dipped into the ink. 6 indicates an annular flange, or wall on said cover which extends down into the outer receptacle 2, and 7 indicates the shot carried in said outer receptacle, into which the said annular flange or wall 6 enters.

Having thus described the several parts of my invention, its operation is as follows: A sufficient quantity of shot is poured into the outer receptacle 2, and the ink-receptacle 3 is filled with ink. The cover 4 is placed in position, the wall or flange 6 thereof being 70 pressed into the shot a sufficient distance to allow the end of the cone-shaped portion of said cover to enter the ink. It is obvious that when the cover is in this position only that portion of the surface of the ink which 75 is within the end of the cone-shaped portion 5 is exposed to the action of the air, while the remaining surface of the ink is sufficiently sealed against evaporation on account of the annular flange 6 of the cover 4 extending 80 down into the shot 7, it being of course understood that the shot employed is of a size which will be readily displaced by the flange 6. As the ink in the ink-receptacle 3 is used, the cover 4 is depressed so as to always keep 85 the end of the cone-shaped portion 5 in the ink, the highest position of the cover being shown in dotted lines in Fig. 2. When, of course, the ink gets so low that the walls of the receptacle 3 prevent a further lowering 90 of the cover 4, the said receptacle 3 should be refilled.

The construction shown in Fig. 3 is essentially the same as that shown in Fig. 2, with the single exception that the ink

can be removed for cleaning without in any way disturbing the outer receptacle 2.

Referring now to Fig. 1, it will be seen that the shot 7, while acting as a seal for the ink 5 and while supporting the cover 4 at any desired point, also acts as a penholder and pen-wiper, as after using the pen the same is inserted in the shot between the flange 6 of the cover and the wall of the outer receptacle 2, 10 and the pen can be allowed to remain in the shot, if desired, thereby utilizing the device as a penholder, or after inserting the pen in the shot the same may be withdrawn and racked on a separate rack, if so desired.

Having thus fully described my invention, 15 it is of course obvious that any other suitable material or a yielding mass other than shot can be employed, and it is also obvious that my invention is susceptible to many slight 20 changes in details of construction without departing from the limit and scope of my invention, and I consider myself clearly entitled to all such changes and modifications.

What I claim as my invention, and desire to 25 secure by Letters Patent of the United States, is—

1. In an ink-well, the combination of an

outer receptacle to receive shot, an inner ink-holding receptacle, a cover having a cone-shaped portion adapted to enter the said ink-receptacle and an annular flange or rim on said cover adapted to enter said outer receptacle and to be pressed into and supported by the shot in said outer receptacle to support the end of the said cone-shaped portion of 35 said top below the surface of the ink in said ink-receptacle, substantially as described.

2. In an ink-well, the combination of an outer receptacle, an ink-receptacle, a cover having a portion thereof extending within the 40 said ink-receptacle and a portion thereof extending within the said outer receptacle, a yielding mass within said outer receptacle adapted to be displaced by the portion of the cover extending within said outer receptacle, 45 said material being also adapted to receive the pen to wipe the same, substantially as described.

In testimony whereof I affix my signature in presence of two witnesses.

STEPHEN G. BALDWIN.
